UNITED STATES PATENT OFFICE.

JOHN WINGER, OF BROOKLYN, NEW YORK.

ATTACHMENT FOR PENS.

No. 892,791.

Specification of Letters Patent. Patented July 7, 1908.

Application filed December 8, 1906. Serial No. 346,910.

To all whom it may concern:

Be it known that I, JOHN WINGER, a citizen of the United States, residing at Brooklyn, in the county of Kings and State of New York, have invented new and useful Improvements in Attachments for Pens, of which the following is a specification.

My invention relates to pens and more particularly to attachment for same which are adapted to hold a supply of ink. These and other objects of the invention are more fully set forth in the following specification and the appended claims, and illustrated in the accompanying drawings where it will be seen that like reference characters are used to designate the same parts in the various figures.

Figure 1 is a perspective view of a pen from the under side showing my improved attachment. Fig. 2 is a longitudinal sectional view of the pen and the attachment. Fig. 3 is a perspective view of the attachment.

In the use of writing pens particularly those of a large size and where a large pen is used in writing the records of other manuscript the difficulty has been in securing a pen with a large concavity near its point which will hold the necessary supply of ink and it is with this object in view that the present invention is intended.

The invention consists of a triangular piece of thin metal curved from its point towards the rear, the point coinciding with the point of the pen 11 and at the extreme rear of the curved face 12 and from the line 13 the attachment slopes backward and upward in a plane face 14. From the face 14 extend two lips or fingers 15 which are intended to embrace the edges of the pen at its widest portion.

As will be seen in Fig. 2 the inclined face 14 approaches the body of the pen so as to form a chamber 16 to contain the supply of ink and partly inclose it to keep the same from being spilt or lost.

It is obvious that the angle of the lips 15 may be varied to conform with any style of pen or likewise the width of the attachment may be varied for the same purpose, also the angle of the face 14 may be varied to admit of more or less ink to the chamber 16 as the pen is dipped into the ink stand.

A desirable feature in this invention is that the attachment may be made of some non-corrosive material and applied to any pen so that as one pen wears out it can be attached

to a new pen so that it will last for a long time.

What I claim as new and desire to secure by Letters Patent is:

1. A fountain attachment for pens comprising a plate having a tapering concavo-convex tongue to bear under and against the nibs of the pen, and having a broadened plane portion bent at an oblique angle upwardly and rearwardly from the rear edge of said tongue and tapered longitudinally to fit between and bear against the sides of the pen in rear of the nibs, whereby the tongue and oblique portion when applied form with the adjacent parts of the pen an ink reservoir whose greatest depth is at the angle of intersection between such parts of the attachment.

2. A fountain attachment for pens comprising a plate having a tapered concavo-convex tongue to bear under and against the nibs of the pen, and having a broadened plane portion bent at an oblique angle upwardly and rearwardly from the rear edge of said tongue and tapered longitudinally to fit between and bear against the sides of the pen in rear of the nibs, said plane portion being formed at its side edges with diverging longitudinal flanges adapted to be bent outwardly and upwardly to engage the lower edges of the sides of the pen.

3. In combination with a pen, a fountain attachment comprising a plate having a tapered concavo-convex tongue bearing against the underside of the nibs of the pen, and having a broadened rear portion extending upwardly between the sides of the pen at an oblique angle and tapered longitudinally to conform to the internal contour of the side walls of the pen body, whereby an ink reservoir is formed between the attachment and nibs and adjacent portion of the body of the pen, said reservoir being deepest at the junction of the body portion of the pen with the nibs and the portions of the attachment with each other, the side edges of the oblique end portion of the attachment being provided with flanges bent outwardly and upwardly to engage the side edges of the body of the pen.

In testimony whereof, I affix my signature in presence of two witnesses.

JOHN WINGER.
